GLOW SWITCH

Walter E. Carpenter, West Caldwell, and Charles Wiener, Bloomfield, N. J., assignors to Westinghouse Electric Corporation, East Pittsburgh, Pa., a corporation of Pennsylvania

Application May 10, 1947, Serial No. 747,288

3 Claims. (Cl. 200—113.5)

1

The present invention relates to what are now known to the art as glow switches employed for the starting of discharge lamps, particularly of the fluorescent type and provided with filamentary electrodes adapted to be preheated prior to initiation of a discharge.

In order to start a fluorescent lamp the glow switch must perform a sequential operation of first completing a heating circuit for the filamentary electrode of the lamp and, after maintaining the circuit closed for a sufficient period of time to assure the filamentary electrode being heated to maximum electron emissivity, open the heating circuit. Because of this sequential operation appreciable time elapses before the lamp actually becomes lighted which time varies considerably with individual glow switches. For this reason certain standards have been established as to maximum allowable time lag in the operation of the glow switch before starting of the lamp, which results in rather high salvage for the manufacturer, since the switch must be completely fabricated and tested before it can be determined that a given switch meets the standard requirements. One of the salient faults necessitating rejection of many glow switches is because they are too slow in their operation in closing the lamp filament heating circuit. Such defect is attributable to the fact that, at the pressure of the gas employed in the glow switch, a certain spacing is required between the electrodes which required spacing becomes altered during fabrication of the glow switch and thus changes the breakdown voltage thereof.

Another factor bearing on the efficiency of the glow switch and its meeting standard requirements is in energy consumption during starting of the discharge lamp. Inasmuch as a current limiting device, customarily in the form of an inductance, is necessarily included in the circuit for the lamp, the interruption of the heating circuit for the filamentary electrode by the glow switch causes a high transient voltage or surge from the inductance which is applied across the preheated electrodes of the lamp to facilitate starting thereof. Since the glow switch and the lamp are in electrical parallel relation at the moment of the high transient voltage surge, it is essential that the glow switch consume a minimum of energy so that the full value of high transient voltage be available for the lamp, to facilitate more rapid starting and regardless of the half-wave of the alternating current cycle during which the glow switch opens the filament heating circuit.

2

It is accordingly the primary object of the present invention to provide a glow switch which operates with a minimum time lapse in performing its sequential operations.

5 Another object of the present invention is the provision of a glow switch wherein the spacing of the electrodes is maintained uniform during fabrication and throughout the life of the switch and thus the breakdown voltage necessary to establish the glow discharge in the switch remains uniform.

10 Another object of the present invention is the provision of a glow switch which is exceptionally economical to manufacture yet positive and rapid in its operation to start a discharge within a minimum of time lag.

15 Another object of the present invention is the provision of a glow switch wherein the seal of the exhaust tubulation to the envelope is so disposed relative to the electrodes of the glow switch that no mechanical or thermal strain is at any time imposed on such seal.

20 A further object of the present invention is the provision of an envelope for the reception of the elements of a glow switch wherein the various elements can be accurately aligned and fixed during fabrication of the switch.

25 Still further objects of the present invention will become obvious to those skilled in the art by reference to the accompanying drawings wherein:

30 Figure 1 is a longitudinal view in cross-section of a glow switch constructed in accordance with the present invention.

35 Figure 2 is a view partly in cross-section and taken at an angle of 90° to that of Figure 1.

Figure 3 is a cross-sectional view taken on the line III—III of Figure 1.

40 Figure 4 is a cross-sectional view taken on the line IV—IV of Figure 1.

Figure 5 is a cross-sectional view showing one form of apparatus which may be used in connection with a step in the fabrication of the glow switch of the present invention.

45 Figure 6 shows the glow switch in cross-section and in another position of the apparatus during a further step in its fabrication.

Figure 7 is a fragmentary view of the glow switch of the present invention during its tipping-off.

50 Figure 8 is a view of a modification which the completed glow switch of the present invention may take.

55 Referring now to the drawing in detail the glow switch of the present invention comprises

an envelope 5 provided with a pinch seal 6 at one end through which leading-in conductors 7 and 8 extend to the interior of the envelope. At its opposite end the envelope 5 is provided with a small tubulation 9 circumferentially sealed between its ends to the envelope 5, so that the tubulation projects a short distance interiorly and exteriorly of the envelope, and any strain, either in the tubulation or envelope caused by the seal therebetween, is thus remotely disposed particularly with respect to the inner end of the tubulation 9. After exhaustion of the envelope 5 and the filling thereof with a gaseous medium, such as a mixture of approximately 99.6% argon and 0.4% nitrogen, or any other suitable gas to give a break-down ranging from 125 to 145 volts, the tubulation 9 is tipped-off, by heating with a gas flame 10 or the like, and drawing the excess tubing, as shown in Figure 7.

As shown, a pair of electrodes in the form of narrow bimetallic strips 12 and 13, having a coating of metal, such as zinc, on their surface, are supported by the leading-in conductors 7 and 8 and extend longitudinally of the envelope 5, with their inner ends extending a short distance into the open end of the interiorly projecting tubulation 9. It will also be noted that the pinch press 6 has an inwardly projecting portion 14 provided with a small recess or crater 15 therein, surrounding the electrodes 12 and 13 at their points of emergence from the inwardly projecting portion of the pinch press 6, for a purpose to be hereinafter described. Disposed on the surface of the inwardly projecting portion 14, as well as within the crater 15, is a metallic coating, such as aluminum paint 16, applied prior to sealing the portion 14 to the envelope to form the pinch press 6, which coating forms a high resistance conductive path between the leading-in and supporting conductors 7 and 8, so as to maintain the breakdown voltage of the glow switch during operation substantially uniform in daylight and darkness.

By reference now more particularly to Figures 5, 6 and 7, the method of fabricating the envelope for reception of the various elements of the glow switch of the present invention is shown. The tubing 20, from which the envelope 5 is formed, may be held in suitable jaws 22 with such tubing resting on a metallic or refractory rod 23. This rod is provided with a central bore 24 which concentrically supports a smaller diameter tubing 25, from which the tubulation 9 is formed, so that the tubing 25 projects slightly above the line of engagement of the rod 23 with the envelope tubing 20, and thus a short desired distance interiorly of the open end of the envelope tubing 20. A carbon or other suitable mold 26 telescopically engages the envelope tubing 20 which mold is provided with a recess 27 for engaging the upwardly projecting end of the tubing 25 so as to center the latter within the envelope tubing 20. Heat in suitable form such as by gas flames 28, is applied to the lower end of the envelope tubing 20, softening the latter and causing it to flow around the rounded end 29 of the mold 26 and to unite and form an hermetic seal with the smaller tubing 24, as shown by the dotted lines in Figure 5, at a point below the inwardly projecting free end of the tubing 25.

The mold 26 is then withdrawn from the envelope tubing 20 with the jaws 22 subsequently raising the envelope tubing which withdraws the smaller tubing 25 from the recess 24 thus partially forming the envelope 5 as shown in the

inverted position of Figure 6. As will be noted from this latter figure the seal 30, formed between the tubulation 9 and the envelope tubing 20, is somewhat remote from the inner open end of the tubulation 9. This is of importance as hereinbefore mentioned because of the fact that the bimetallic electrodes 12 and 13, which project into such open end of the tubulation 9, are subjected to heat during operation of the glow switch. Since the ends of the electrodes 12 and 13 bear against the inner wall of the tubulation some of this heat is conducted to the end of the tubulation 9 but inasmuch as this end is sufficiently remote from the point of seal between the envelope tubing 20 and the tubulation 9, there is no strain upon the seal as would otherwise be the case if the tubulation were sealed at its end to the envelope tubing 20.

After the sealing of the tubulation 9 to the envelope tubing 20, the completed envelope is inverted, as shown in Figure 6, and again held by the jaws 22, for sealing in of the mount 32. Such mount is preformed and comprises the leading-in and supporting conductors 7 and 8 and which support the bimetallic electrodes 12 and 13, sealed to a glass bead 33 having the aforementioned recess 15 therein and the aluminum coating 16 on its surface. A sealing-head 34 supports the envelope tubing 20 and is provided with small holes 35 engageable by the leading-in and supporting conductors 7 and 8 which, together with the electrode ends projecting into the tubulation 9, centers the mount 32 with respect to the envelope tubing 20. The latter is then again heated, such as by gas flames 36, and upon softening a pair of clamping jaws 37 move in an arcuate direction, as shown by the arrows in Figure 6, to form the pinch press 6, by hermetically sealing the envelope tubing 20 to the glass bead 33, as shown by the dotted lines in Figure 6.

During sealing, the bimetallic electrodes 12 and 13 are naturally also heated and to a higher temperature than during operation of the glow switch. Since the low expansion sides of the bimetals are adjacent each other this causes the ends of the electrodes to engage each other under substantial pressure sufficient to slightly distort the same. Accordingly, upon cooling and completion of the switch, the electrodes 12 and 13 are under a slight tension in an opposite direction, causing them to bear against diametrically opposite sides of the inner wall of the tubulation 9. This results in the maintenance of a uniform predetermined spacing between the electrodes throughout the useful life of the glow switch depending upon the diameter of the tubulation 9. Also during sealing an inert gas, such as nitrogen or the like, is introduced into the envelope tubing 20 to prevent oxidation of the bimetallic electrodes 12 and 13 which would otherwise readily occur, particularly while they are in a heated condition, and effect their subsequent operation.

The partially completed glow switch then moves to the exhaust position where it flashed to degasify the metallic parts while on the exhaust pump, then filled with the aforementioned ionizable medium and sealed off as shown in Figure 7.

Inasmuch as the breakdown voltage of the glow switch is dependent upon the pressure of the ionizable medium employed and the electrode spacing, it can be appreciated that, since the pressure is definitely fixed at the time of introduction into the envelope, the equally defi-

nite fixing of the electrode spacing which remains constant throughout useful life, results in a glow switch having high efficiency and an unusually long useful life. Moreover, since it is desirable that the bimetallic electrodes 12 and 13 of the glow switch be heated as quickly as possible by the ensuing discharge therebetween upon application of a voltage thereto, in order to complete the series heating circuit for the filamentary electrodes of the lamp, so that this time period is invariably below the maximum allowable standard, the crater 15 is provided in the inwardly projecting portion 14 of the pinch press 6. The effect of this crater 15 is that it increases the intensity of the discharge at the crater with very rapid accumulation of heat which is quickly conducted to the axis of bend of the bimetallic electrodes 12 and 13, causing them to engage each other with minimum time delay. If desired this crater 15 may be made of appreciable depth so as to surround the bimetallic electrodes 12 and 13 for a greater portion of their length, as shown in the modification of Figure 8. Also, it will be noted from this latter figure that the electrodes 12 and 13 are provided with contacts 38. This enables a somewhat larger diameter tubulation 9 to be employed when desired while allowing ample passageway for exhaust purposes and yet maintaining constant uniform spacing between the electrodes.

It is also to be noted that the bimetallic electrodes 12 and 13 are very thin and of narrow width in order to increase the transient voltage applied to the lamp upon separation of the electrodes when cooled. As previously mentioned the glow switch is so connected to a fluorescent lamp as to connect the filamentary electrodes in series to the supply source and an inductance element is invariably included in the circuit for the lamp to limit the current supplied to the lamp during operation. Consequently, upon cooling of the bimetallic electrodes of the glow switch and their separation, a high transient voltage or surge is induced in the circuit by the inductance at the instant of separation of the electrodes which is impressed across the pre-heated electrodes of the lamp for initiating the discharge.

However, this high voltage surge alone is insufficient to initiate a discharge in the lamp in the absence of sufficient current flow, and, inasmuch as the glow switch is in electrical parallel with the lamp at the instant of this high voltage surge, it must be designed so as not to rob the lamp of current by limiting current consumption of the glow switch to a minimum thus enabling maximum current to be supplied to the lamp. Moreover, this desirable condition must exist at the moment of the high voltage surge and regardless of which bimetallic electrode 12 or 13 happens to be instantaneously cathode. To this end each bimetallic electrode 12 and 13 is accordingly designed to have as small a surface area as is feasible with manufacturing techniques, since the smaller the surface area of the bimetallic electrodes the smaller the current consumption of the arc discharge momentarily formed in the glow switch at the instant of separation of the bimetallic electrodes, and hence the larger the high transient energy available for the lamp to more positively initiate a discharge therein.

It is believed to be obvious from the foregoing that a glow switch is provided by the pres-

ent invention which operates at high efficiency and throughout a long useful life because the electrode spacing is maintained uniform. Moreover, the tubulation into which the electrodes of the glow switch extend, so as to maintain this uniform spacing, is sealed to the glow switch envelope in such manner that heat from the electrodes and conducted to the tubulation, in no way places a mechanical or thermal strain upon the hermetic seal which would otherwise cause cracking of the seal and destruction of the glow switch. By the provision of a crater for increasing the intensity of the discharge, the bimetallic electrodes are rapidly heated and as rapidly cooled, so that the glow switch performs its sequential operations with a minimum time delay in the starting of a fluorescent lamp. Also, by the provision of bimetallic electrodes of small surface area commensurate with manufacturing technique, the high transient voltage available for starting the lamp is increased which tends toward starting of the lamp on the initial operation of the glow switch and reduces the probability of repetitious operation thereof, before a discharge in the lamp is actually obtained thus still further prolonging the useful life of the glow switch.

Although several embodiments of the present invention have been shown and described it is to be understood that still further modifications thereof may be made without departing from the spirit and scope of the appended claims.

We claim:

1. A glow switch operable for the starting of a discharge lamp comprising an envelope provided with an ionizable medium therein, a pair of normally spaced thermal responsive electrodes in said envelope between which a discharge occurs upon the application of a potential to the switch and operable to engage each other when heated by the discharge to extinguish the latter and thereafter separate upon cooling, and an annular member supported by said envelope interiorly thereof and engaging at least the free ends of said electrodes entirely within said envelope to prevent the strain inherent in said electrodes due to heating during fabrication of the switch from causing too great an electrode spacing and to maintain the spacing therebetween constantly uniform throughout a long useful life of said glow switch.

2. A glow switch operable for the starting of a discharge lamp comprising an envelope provided with an ionizable medium therein, a tubulation of insulating material circumferentially sealed to said envelope at a point removed from one end of said tubulation to project a portion thereof interiorly of said envelope, and a pair of normally spaced thermal responsive electrodes in said envelope between which a discharge occurs upon the application of a potential to the switch and operable to engage each other when heated by the discharge to extinguish the latter and thereafter separate upon cooling, and at least the free ends of said electrodes extending into the projecting portion of said tubulation and each end bearing against diametrically opposite points on the interior wall of said tubulation to maintain the spacing between said electrodes constantly uniform throughout a long useful life of said glow switch.

3. A glow switch operable for the starting of a discharge lamp comprising an envelope provided with an ionizable medium therein, an exhaust tubulation of insulating material of pre-

determined diameter circumferentially sealed to one end of said envelope between the ends of said tubulation to project a portion thereof interiorly and exteriorly of the envelope and sealed-off at its outer end after evacuation and filling of said envelope with the ionizable medium, and a pair of normally spaced thermal responsive electrodes in said envelope between which a discharge occurs upon the application of a potential to the switch and operable to engage each other when heated by the discharge to extinguish the latter and thereafter separate upon cooling, and at least the free ends of said electrodes extending into the projecting portion of said tubulation and the end of each electrode bearing against diametrically opposite sides of the interior wall of said tubulation to maintain the spacing between said electrodes constantly
